ELECTRICAL COMMUNICATION CABLE

Esmond Wassell Smith, Beechcroft, Chislehurst, England, assignor to Canada Wire and Cable Company Limited, Leaside, Ontario, Canada, a corporation

Application May 5, 1949, Serial No. 91,552

In Great Britain May 7, 1948

1 Claim. (Cl. 174—106)

1

This invention relates to communication cables, and is concerned more particularly with multi-core cables capable of carrying a large number of telephone circuits or a smaller number of broadcast or television circuits and incorporating also auxiliary pairs or quads for supervising unattended repeaters.

The invention has for its object to provide a multi-core cable of this type which will be highly efficient electrically but which will be relatively cheap to manufacture and install, light in weight and unaffected by moisture, so that it can be laid in waterlogged or damp locations.

In the past, cables of this type have been made up of two or more tubular coaxial cores of air-spaced construction with an outer conductor consisting of a plurality of long-lay copper tapes, preferably interlocking, or a single longitudinal tape bent to form a cylinder with a longitudinal butt joint, and these coaxial cores have been laid up with a number (e. g. twelve) of ordinary paper insulated telephone quads for servicing the repeater stations, the composite cable being finally lead sheathed overall to provide security against ingress of moisture. It will be apparent that such constructions are extremely heavy and that ingress of moisture, due for example to mechanical damage of the lead sheath, would quickly lead to the waterlogging of the entire system and interruption of transmission.

The invention broadly stated resides in employing in the cable insulating materials which are both extremely good dielectrics and also substantially impervious to water, thus enabling the use of a lead sheath to be eliminated and economizing in both weight and cost.

According to the present invention the cores in the communication cable comprise a central conductor, an intermediate layer of solid insulation material, an outer conductor consisting of a conductive tape applied longitudinally over the solid insulation with its edges overlapping and secured in position by a conductive tape applied helically over the longitudinal tape and an outer thermoplastic sheath applied over said outer tape, said solid insulation layer consisting of polyethylene or a material having substantially similar dielectric characteristics and resistance to water penetration.

In accordance with one feature of the present invention a coaxial core for use in a communication cable of the type referred to consists of a central conductor separated by a solid thermoplastic water-resistant dielectric from an outer conductor composed of a single conductive tape

2

applied longitudinally with a substantial overlap and bound in position by a short lay conductive tape applied with overlapping edges, the whole being covered by a lapping of water-resistant non-metallic tape.

In accordance with another feature of the invention a multi-core communication cable of the type referred to comprises a number (preferably two or four) of coaxial cores as set out above laid up with a plurality of twisted twin or quad cables providing repeater supervisory and control circuits, the conductors of such twins or quads being insulated with a solid thermoplastic and water-resistant dielectric, and the whole being filled circular and served with jute or other conventional material, lightly armoured with steel tape and finally covered with compounded fabric tapes or jute yarn.

Preferably the pairs or quads consist of single strand conductors insulated with dielectric material coloured as required for identification, twisted together and filled circular with a similar dielectric, and advantageously several (say three) such pairs or quads are laid up together 25 so as to form a convenient assembly for laying in the interstices between the coaxial cores.

The dielectric material employed throughout is preferably polyethylene or a mixture thereof with other materials such as polyisobutylene, but the 30 cores of the signal pairs may in some cases be insulated with a lower grade of water-resistant dielectric, such as polyvinyl chloride or similar compounds.

The invention is illustrated in the accompanying drawing which is a perspective sectional view of a communication cable having four co-axial cores laid up with twin cables.

Referring to the drawing, the cable comprises four co-axial type cable cores each indicated generally at C laid up with twin cables indicated at T, of which there are five, one being central and the remainder spaced in the recesses between adjacent cores C.

Each core C comprises a central conductor 45 enclosed in a solid layer 2 of insulation consisting of a thermoplastic water-resistant dielectric. Applied to the insulation layer 2 is a single conductive tape 3, which is wrapped longitudinally about the core so formed, with its edges overlapping and held in position by a metal tape 4, the latter being wound over the conductor 3 with a short lay and applied with overlapping edges. The whole is then finally covered with insulation tape 5. The dielectric used in the 50 composition of the insulation layer 2 and of the

tape 5 preferably consists of polyethylene. In the embodiment shown each twin cable T consists of two cores 6, 6, of plain copper wire covered with a layer of insulation 7 also preferably of polyethylene and united in an outer covering of insulation 8 also of polyethylene. The four cores C and five twin cables T are laid up in the positions shown and enclosed in a jute bedding 9 over which are wound steel armouring tapes 10, the whole being finally enclosed in an outer 15 jacket serving 11.

An example of a two core cable in accordance with the invention comprises two coaxial cores each of which consists of a single conductor, e. g. 0.096" plain copper wire, insulated with polyethylene to a diameter of 0.350". The coaxial return conductor is a single copper tape, approximately 1.3" x 0.010", applied longitudinally with an overlap of approximately 50%, and may be crimped transversely at intervals to enhance its flexibility. This return conductor is bound down by means of a single copper tape applied with a short lay and a 20% overlap followed by a polyethylene tape likewise applied with a short lay and a 20% overlap, the overall size of each 25 co-axial core being approximately 0.407".

The signal pairs for supervising and controlling the repeaters in a two core cable are made up of two cores each comprising a small plain copper wire, 0.028" in diameter, covered with a solid insulation of polyethylene (coloured as required) to 0.068". Two such cores are twisted together and then filled circular and belted with polyethylene to a diameter of 0.152". Three such pairs are then laid up together with a lay opposite to that of the individual pairs to give a six-core assembly having an overall diameter of approximately 0.32".

Laid up with the two coaxial cores, with their outer surfaces in contact, are two groups of three signal pairs and jute wormings to produce a circular form. This assembly is then served with cutched jute yarn and armoured with two steel tapes applied helically with a 50% gap and breaking joint so as to provide a closed armour layer. The cable is finished off by applying two compounded Hessian tapes to give some degree of protection to the steel tapes. The overall diameter of the finished cable is of the order 1.33".

Each of the two coaxial cores constructed as described has a high frequency impedance of approximately 52 ohms and an attenuation at 1.05 mc/sec. of approximately 4 db/km. Assuming, therefore, an attenuation limit of 40 db, the repeater spacing will be approximately 10 km. and since the estimated near-end cross talk is better than 85 db at 60 kc/sec. a pair of such coaxials will provide 240 telephone circuits. Each telephone channel occupies a frequency band of 4 kc/sec. and the channels are packed closely 60 together in the frequency spectrum, but each

super-group of 60 circuits is separated by a small gap. The 240 circuits are assembled in four super-groups covering the frequency range 60 to 1052 kc/sec. with the "go" channels in one coaxial and the "return" channels in the other.

Obviously, by reducing the repeater spacing it is possible to accommodate a greater number of telephone circuits. For example, with a repeater spacing of 6.5 km. ten supergroups can be accommodated, giving 600 circuits per pair of coaxial cores in the frequency range 60 to 2540 kc/sec., at which higher frequency the attenuation is approximately 6 db/km.

It will be understood that the signal pairs are employed only for supervisory and control purposes in connection with the repeaters, which may be at unattended stations and be fed with power via the inner conductors of the coaxials.

I claim:

20 A multi-core high frequency land communication cable, comprising in combination a plurality of high frequency co-axial cores, each co-axial core comprising a central conductor, a solid layer of polyethylene enclosing the conductor, an outer conductor comprising a first conductive tape applied longitudinally over the polyethylene layer with an overlap along its edges and a second conductive tape wrapped with a short lay over the first conductive tape, and a layer of electrical insulation comprising a polyethylene tape applied helically over the second conductive tape; a plurality of auxiliary cores laid up in the interstices between the co-axial cores, each of the auxiliary cores comprising a conductor and a solid layer of polyethylene enclosing the conductor; an insulating bedding in which the cores are embedded; a protective armouring tape over the bedding; and an insulating serving enclosing the armouring tape.
